INTERMITTENT MECHANISM FOR MOTION-PICTURE PROJECTING MECHANISMS

John W. Lang, Jr., Chicago, Ill., assignor to
De Vry Corporation, Chicago, Ill., a corporation
of Illinois

Application September 9, 1950, Serial No. 184,004

1 Claim. (Cl. 88—18.4)

This invention relates to certain new and useful improvements in intermittent mechanism for motion picture projecting mechanisms. More particularly the invention concerns the provision of a film actuating claw having a plurality of equally spaced apart teeth for engaging the apertures of a film for intermittently moving the film relative to an apertured plate over which the film strip is payed in a manner well known in the art.

An object of this invention is to provide the tooth of the claw which is commonly called the "action tooth," with a shoe formed of wear resisting material, thereby to extend the life of the claw. This action tooth is the only tooth of the claw which engages the film during normal perfect sprocket operation, the other teeth of the claw on opposite sides of the action tooth being auxiliary teeth and normally engaging the film only in the event of a tear or rupture of the film at the aperture engaged by the action tooth. Consequently, by reason of the heavy duty imposed upon this action tooth in the intermittent moving of the film, unless protected it soon becomes worn and rendered ineffective for its intended purpose. As before stated, an object of this invention is to protect this action tooth against wear.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a fragmentary perspective view of an intermittent mechanism showing my improved claw associated therewith;

Fig. 2 is a fragmentary side elevational view of the same showing the film in longitudinal section;

Fig. 3 is an edge view taken substantially on line 3—3 of Fig. 2;

Fig. 4 is an enlarged side elevational view of the claw embodying my invention;

Fig. 5 is an edge view of the same taken substantially on line 5—5 of Fig. 4; and

Fig. 6 is a fragmentary view similar to Fig. 4 showing a modified form of construction.

The objects of this invention are best accomplished by the preferred form of construction as shown in the accompanying drawings, in which drawings I have illustrated a slide 10 providing an integral claw 11 consisting of an action tooth 12 equally spaced apart from adjacent parallelly extending auxiliary steel teeth 13. This action

tooth is so-called because in the normal operation of a moving picture projecting apparatus this tooth is the only tooth of the claw which engages the film, the other two steel teeth 13 being auxiliary teeth due to the fact that their engagement with the film takes place upon enlargement of the aperture or tear of the film in the area of the aperture which is engaged by the action tooth 12.

Such being the case, it is manifest that the action tooth in its operation of moving into and out of the aperture to engage the film will in a relatively short time be worn to a condition such that it will fail to perform the function required of it. To eliminate this undue wear upon the action tooth, I provide a shoe 14 of elongated flat formation and of a thickness substantially equal to one-half of the thickness usually required of an action tooth.

The claw provides a forwardly extending steel ledge 15 which is of a thickness equal to the thickness of the shoe 14 and which ledge 15 and shoe 14 together provide the action tooth. Inwardly of this ledge 15 and extending into the body of the claw 11 is a slot 16 into which the inner end portion of the shoe 14 frictionally fits. It is preferable that the shoe 14 be welded or cemented by a suitable cement within the slot 16 and to the ledge 15. This shoe may be formed of relatively hard material, such for example, a sapphire. This shoe 14, when projected into the film aperture, presses down on the film to pull the same down. The abrasive effect of the film edge upon the shoe is resisted by virtue of the hardness of the shoe. Reciprocation of the slide 10 is accomplished in a manner substantially similar to that disclosed in United States Letters Patent No. 2,420,444, granted May 13, 1947, on an intermittent mechanism. In accomplishing this reciprocation there is employed a cam 17 mounted on a shaft 18 and operating in a slot 19 formed in the slide 10.

Oscillation of the slide relative to its mounting 20 is likewise accomplished in substantially the same manner as that disclosed in the aforesaid patent and in which there is employed a cam 21 operating in a slot 22 formed in the slide 10.

In the form shown in Fig. 6 I provide as the intermediate tooth a sapphire insert 14' mounted in a slot 15' and secured therein by cement or the like.

By the foregoing construction I have provided a claw with an action tooth capable of withstanding the undue wear normally imposed upon such tooth. This I accomplish by a structure

which is substantially simple and economical in manufacture.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claim.

Having thus described my invention, what I claim as new and desire to protect by Letters Patent is:

A device of the class described comprising a slide, an intermittent film mechanism, a claw integral with the slide at one end thereof and comprising an action tooth and auxiliary teeth on opposite sides of the action tooth in parallel relation with respect thereto, said action tooth comprising a ledge having relatively flat sides and providing a slot extending beneath and in a substantially horizontal plane with respect to one of said sides, a shoe formed of wear resisting

material and of elongated formation having one end thereof adhesively fixed in said slot with a side thereof in intimate and parallel relation with a side of said ledge and having its free end portion extending beyond the edge of said ledge and terminating in the same vertical plane with respect to the auxiliary teeth.
